Primary Examiner — Paula Greene(74) *Attorney, Agent, or Firm* — Sterne, Kessler, Goldstein & Fox P.L.L.C.(57) **CLAIM**

The ornamental design for an earpiece, as shown and described.

DESCRIPTION

FIG. 1 is a top rear perspective view of an earpiece showing our new design;

FIG. 2 is a front view thereof;

FIG. 3 is a rear view thereof;

FIG. 4 is a side perspective view thereof;

FIG. 5 is a top view thereof; and,

FIG. 6 is a bottom view thereof.

The broken lines depict portions of the earpiece and environment that form no part of the claimed design.

PATENT NO. : D792,378 S
APPLICATION NO. : 29/540941
DATED : July 18, 2017
INVENTOR(S) : Brunner et al.

Page 1 of 1

It is certified that error appears in the above-identified patent and that said Letters Patent is hereby corrected as shown below:

On the Title Page

In the "Related U.S. Application Data (60)" section, Line 8, replace "application No. 29/441,334, filed on Jan. 3, 2001" with --application No. 29/441,334, filed on Jan. 3, 2013--.

In the DESCRIPTION section replace "The broken lines depict portions of the earpiece and environment that form no part of the claimed design" with --The broken lines in the figures show portions of the earpiece or environment that form no part of the claimed design--.

Signed and Sealed this
Nineteenth Day of December, 2017

Joseph Matal
Performing the Functions and Duties of the
Under Secretary of Commerce for Intellectual Property and
Director of the United States Patent and Trademark Office
